UNITED STATES PATENT OFFICE

HEINRICH ZEMKE, OF BERLIN, GERMANY

WASHING MACHINE

Application filed September 20, 1930, Serial No. 483,294, and in Germany July 28, 1930.

This invention relates to a novel washing bell by means of which a better and at the same time a more rapid washing effect is obtained without thereby detrimentally affecting the fabric of the washing. The advantages of the novel washing bell consist in that it works with a double effect. During the movement of the inner body the washing situated under the washing bell is washed by means of air and at the same time a further cleaning takes place by means of the small suction cups, a large number of which are provided on the inner body. These many small specially constructed suction cups in conjunction with their arrangement possess important advantages. It is thus possible to thoroughly wash the entire surface and every portion of the washing within the washing bell. The individual suction cups are in no way interconnected. They are pressed with the wide suction portion separately onto the washing. Each individual suction cup thus produces a hermetic shutting off of that portion of the washing which during the subsequent drawing up intensively flushes the fibres of the washing with the lye and draws out the dirt. The many separate suction cups are so arranged that they jointly form a single washing surface which, being continuously in up and down movement, produces a yielding, gentle yet perfect washing effect.

An embodiment of the invention is illustrated diagrammatically in longitudinal section by way of example in the accompanying drawing in which:

Fig. 1 shows the washing bell in inoperative position.

Figs. 2 and 3 show the effect of the suction cups during the washing operation.

According to the invention a thin frame 5 of metal or the like is shiftably arranged in a washing bell 1, 2, which frame is provided with a plurality of separate elastic suction cups 11. These suction cups 11 have a wide suction surface 13, a narrow middle portion or neck 14 and a wide rear portion 15. Owing to this construction they can easily be inserted in bores or recesses 10 in the frame 5 and are properly guided in the

metal frame so that the suction cups can be brought to action during the washing operation. The individual suction cups inserted in the frame 5 form together a separate washing surface situated under the frame. 55 On the rear side of the frame 5 catches 16 are provided between which a rigid plate 17 is arranged which is connected to a handle rod 4. This latter serves for actuating the frame 5.

To facilitate the exchanging of the suction cups the plate 17 is slidably mounted under the catches 16. By lifting the plate 15 the suction cups are relieved on the rear side of their neck 14. The suction cups 11 mounted in the frame 5 are operated by means of the frame 5 and the plate 17 so that the interior surface 12 of these cups is pressed completely onto the washing without the cups being able to yield laterally. 70 The metal parts may be of thin cross-section in order to reduce the weight of the washing bell and facilitate manipulation. The spring 18 mounted on the handle rod 4 facilitates the lifting of the bell and retains the 75 handle rod 4 with the pressure plate 17 always in raised position. Thus, the suction cups are not unnecessarily loaded, they can expand and retain their elasticity.

If the bell is operated, the frame 5 is first 80 depressed by means of the handle rod 4 and pressure plate 17, air and lye being at the same time forced out of the bell through the washing. As soon as the suction cups 11 have been pressed onto the washing by the 85 further downward movement of the frame 5, the interior portion 12 of the suction cups 11 being pressed flat and completely filling the bell under the frame 5 so that the lye is pressed directly through the washing. The 90 portion of the washing situated under the washing bell is, after the above described treatment, subjected to a further cleaning effect by the many suction cups 12 which also act directly on the washing.

This double effect during the upward movement of the bell with pressing effect according to the invention is repeated amplified during its upward movement. The individual suction cups 11 owing to their 100

shape produce a strong suction effect. During the lifting of the washing bell the suction cups first become detached in that they return from their flattened shape into their initial shape. Thus the lye is drawn through the washing on the entire washing surface covered by the suction cups. As the frame 5 continues to ascend, a suction effect is produced thereby in the washing bell which again acts on the fabric of the washing and effects the above described action of the suction cups. Consequently a double effect is produced by pressing during the downward movement of the washing bell and by suction during the upward movement thereof, so that the time required for washing is considerably reduced and a perfect washing effect obtained.

I claim:

20. 1. A washing implement, comprising in combination a washing bell, a metal frame having top and bottom parts and sides connecting the same movable in said bell, a plurality of separate elastic suction cups in said frame forming a separate washing surface under said frame, a movable plate within said frame and adapted to engage said suction cups, and a handle engaging said plate to raise and lower said frame in said bell.
25. 2. A washing implement, comprising, in combination, a washing bell, a metal frame movable in the bell having top and bottom parts and sides connecting the same, a plurality of separate elastic suction cups in said frame and forming a separate washing surface below said frame, each of said elastic suction cups having an intermediate contracted neck portion, there being apertures 40 in said bottom part of said frame receiving the necks of said cups, whereby the latter are detachably held in position on said frame, a movable plate within said frame and adapted to exert pressure upon said 45 frame and suction cups, and a handle on said plate whereby to raise and lower said frame in said bell.

In testimony whereof I affix my signature.

HEINRICH ZEMKE.
